UNITED STATES PATENT OFFICE

MANUEL HUMBERTO PÉREZ, OF SAN PEDRO SULA, CORTEZ, HONDURAS, ASSIGNEE TO
ADRIANA GUZMAN, OF NEW YORK, N. Y.

ELECTRIC SADIRON

Application filed September 29, 1926, Serial No. 138,424. Renewed December 12, 1928.

This invention relates to electrically heated sad irons and to means for heating the same.

Electrically heated sad irons of the usual type are ordinarily provided with self-contained heating units, in the form of resistance coils, located therein, current being supplied to such units, to heat the iron, through a conductor cord coupled to the iron itself when in use and which conveys the electricity therefrom to a source of current, such as a house lighting system. The conductor cord is thus manipulated with the iron in the service use of the latter and besides being the cause of much annoyance and inconvenience for this reason, is a source of danger for many other reasons well-known to those versed in the art. In order to overcome the known objections to the use of a conductor attached to and movable with the iron, it has been proposed to employ an electrically heated stationary base or stand on which the iron is placed when it is desired to heat it, the conductor being attached to the base, instead of to the iron, to supply the electric current to the heating units directly mounted in the base, thus obviating the objectionable use of a conductor cord movable with the iron. This removal of the heating elements from the iron itself is, however, wasteful of current and heat, since the iron, in the absence of the heat stored up in the heating elements, becomes cooled more quickly and has to be more frequently heated and, during the use of the iron, the heat stored up in the base is largely evaporated and lost.

One object of my invention is to provide an iron and heating means therefor which overcomes these several objections, and in which the heating units are contained in the iron itself and the current supplying connections for the same, including the conducting cord, are attached to and contained within a base on which the iron is to be placed to be heated, the iron carrying current controlling connections and the iron and base having coacting circuit making and breaking devices coupled and uncoupled when the iron is respectively applied to and removed therefrom, whereby the conductor cord and

other inconvenient extraneous parts are removed from the iron, while the heating units are retained in the iron, thus maintaining the stored heat of the heating units in the iron and at the same time freeing the iron from the annoyance and dangers incident to having the conductor cord attached thereto and necessarily movable therewith.

Another object of the invention is to provide a reliable and efficient mode of mounting the resistance units and simple and effective current controlling means whereby, in the event of the burning out of one unit, another unit may be coupled up for action; also to provide means whereby both units may be employed to supply the heat desired.

Still another object of the invention is to provide an iron the acting surface, at least, of which is composed of a material which is an electric insulator, and thus adapted to reduce liability of short circuits and shocks to the operator, and which at the same time has the capacity of being highly heated but of slowly giving off its heat to the atmosphere, thus producing an iron which will not quickly cool but will retain its heat for a long period after being heated.

Still another object of the invention is to generally improve and increase the efficiency of irons of this character.

The invention consists of the features of construction, combination and arrangement of parts, hereinafter fully described and claimed, reference being had to the accompanying drawings, in which:

Figure 1 is a view, partly in side elevation, and partly in vertical longitudinal section, of a sad iron embodying my invention.

Figure 2 is a sectional plan view on line 2—2 of Figure 1.

Figure 3 is a vertical transverse section, on a reduced scale, on line 3—3 of Figure 1.

Figure 4 is a plan view of the hand wheel and pointer.

Figure 5 is a detail section showing one of the contact fingers coacting with the brushes.

Figure 6 is a vertical, longitudinal section through the base or stand and the body of the iron resting thereon.

Figure 7 is a top plan view of the stand.

Figure 8 is a vertical longitudinal section on line 8—8 of Figure 7.

Figure 9 is a similar view on line 9—9 of Figure 7.

Figure 10 is a cross-section on line 10—10 of Figure 9.

Figure 11 is a cross-section on line 11—11 of Figure 7.

Figures 12 to 14, inclusive, are views showing the parts of the switch mechanism in different working positions and showing also related positions of the hand wheel with dial thereon.

Figure 15 is a view of the form or core and the resistance units wound thereon.

In carrying my invention into practice, I provide a sad iron proper 1, and a base or stand 2 on which the iron is adapted to be rested when not in use or while it is being heated for use, the two being normally separate units but adapted for cooperation for the heating function so that the iron may be employed in accordance with the foregoing statement of the objects of the invention and as hereinafter fully described.

The iron 1 comprises a hollow body portion 1^a forming a heating chamber 3 and having a smooth bottom ironing surface 4, a cover plate 5 closing the top of said chamber 3, a top or housing plate 6, standards 7 fixed to and rising from the plate 6, and a handle 8, of insulating material, carried by the standards, whereby the iron is adapted to be carried and manipulated in the usual way. These parts are detachably united at the point and heel corners by bolts 9 and 10, respectively, engaging threaded countersunk bushings 11 and 12 lying flush with the bottom of the iron, the bolt 9 and its bushing 11 forming one of the circuit contacts and conductors, as hereinafter described. The chamber 3 encloses a heating element of novel type, said element comprising a form-block or core 13 of porcelain or other suitable electric insulating material, of the general shape of the iron body and suitably secured in chamber 3, and having its edge portions provided with two sets of alternately disposed notches 14 and 15, said block carrying at its toe portion a binding post 16 and at its heel portion a pair of spaced binding posts 17 and 18. A resistance wire or wires 19 is or are anchored to the binding post 16 and thence wound spirally around the block, from the toe to the heel end thereof, and engaging the respective notches 14 and 15, forming units 20 and 21 terminating at the heel end of the block and fixed to the respective binding posts 17 and 18. A continuous double resistance unit is thus provided capable of being used as such, and of which the members 20 and 21 form separate and independent resistance units capable of being used as such, maxi-

mum simplicity of construction being thereby secured. These resistance units may be of the same or different resistance values as desired, by varying their effective lengths, or making them of wire sections of different resistances. Fastened to the upper surface of cover 5 are pole plates 22 and 23, and bolt 9, hereinbefore described, passes upwardly through cover 5 and plate 22 and thus electrically connects the bushing 11 with said plate 22, the bushing, bolt and plate forming one pole of the electrical connections to the coil. Plate 23 is provided with a down-turned contact 24 and forms therewith the other pole of the electrical connections to the coil, as hereinafter fully appear. The posts 17 and 18 extend from block 13 upward through cover plate 5, and electrically connected with post 17 are spaced contacts 25 and 26 and electrically connected with post 18 is a contact 27. Carried also by the cover 5, for coaction with the brush 26', are contacts 26^a—26^b, which are connected respectively with the coil windings 21 and 20 at suitable points in the length thereof, i. e., at such points as may be desired in practice for employing different effective amounts of the coil windings both less than the sum total of the winding in order that the heating action may be varied, as hereinafter described.

Switch mechanism carried by the iron is provided for controlling the flow of current to the resistance units and thus governing the heat supplied therefrom to the iron to heat the latter to any given degree within a given period of time. This switch mechanism comprises a pair of switch plates 28 and 29 mounted, like the plates 22 and 23, on the cover 5 and between the same and the top plate 6, which plate 6 is hollowed on its underside to provide an enclosing chamber for the said switch mechanism. The switch plate 28 is mounted centrally to swing laterally on a pivotal axis 30 and is provided with a spring contact brush 26', while the switch plate 29 is pivotally coupled, as at 31, to the plate 28, to swing laterally, and is provided with spring contact brushes 25' and 27' and electrically connected by the pivot member 31 to said plate 28. The two plates are mechanically coupled to swing laterally in reverse directions by means of a contact member or roller 32 carried by the forward end of the plate 29 which slidably and pivotally engages a slot 33 in the rear end of the plate 28, the member or roller 32 being made of some suitable electric non-conducting material, so that the switch plates 28 and 29 are pivotally coupled for movement in unison but are at all times electrically insulated so far as any direct electrical connection between them is concerned. The other or forward end of the switch plate 28 is provided with a slot 34 receiving a roller 35 on one

end of an actuating lever 36, said roller 35 forming an electrical connection between the plate 28 and lever 36, and the latter being pivotally connected at its opposite end to 5 the plate 22 by the pin or stud 37, which also electrically connects said members 36 and 22 together. The lever 36 is also provided with a boss 36' having an angular socket 38 to receive the angular end of an actuating 10 shaft 39, extending upwardly in advance of the front standard 7 and suitably journaled in the top plate 6 and in bearings on said standard and carrying at its upper end a hand wheel 40, by means of which the lever 15 36 may be rocked laterally in either direction to transmit motion to the switch plates. The hand wheel 40 is provided with a dial bearing therein the indications X, 0, 1, 2, for co-operation with a fixed pointer 41 on the 20 handle 8, so as to give indication for positive adjustments of the hand wheel to adjust the parts of the switch mechanism to the positions shown in Figures 5 and 12 to 14, inclusive, for controlling the supply of electric 25 current to the resistance units.

The base or stand 2 comprises in its construction bottom and top plates or sections 42 and 43 provided on their meeting faces with spacing projections 44, said plates 42 30 and 43 being united by screws or other suitable fastenings 44'. Extending longitudinally between the plates 42 and 43 and held confined in grooves between the spacing members 44 are conductor rods 45 and 46, 35 the forward ends of which project into a space between the forward ends of the plates 42 and 43 and are adapted to be engaged by conducting bushings 47 and 48 in the connection plug 49, to which the feed conductors 40 50 are secured, the positive and negative wires of said conductor being coupled to the respective bushings 47 and 48. The plug body 49 may be made of porcelain or other suitable insulating material formed in sections 45 united by screws or other suitable fastenings 51 to admit of the primary reception of the bushings 47 and 48. These bushings, if desired, may be split for a spring action to grip the rods, the ensure a positive connection between them. Plug 49 is adapted 50 to be inserted and held between the spaced forward portions of the plates 42 and 43, and the conductor 50 in practice may lead from the outlet of a house-lighting or other suitable electric circuit. The two conductors 45 and 46 are electrically insulated by the material of the base plates from each other, but the conductor 45 is electrically connected with a contact piece or stud 52 lying flush 55 with the upper face of the top plate 43 at its toe portion, while the conductor 46 is electrically connected with a contact plate or piece 53 located at the heel end of the base. The plate 43 is provided 60 with a raised flange 54 extending around its toe portion and sides, forming a shallow chamber or recess to receive the bottom of the iron 1, said chamber or recess being open at the rear to permit the iron to be slidably inserted and removed. The flange 54 further serves as a guide to properly position the iron so that, when the iron is seated thereon, the contact member 11 thereof will engage the contact member 52, while the contact member 27 will engage the contact member 53, thus automatically coupling the circuit supplying connections on the base with the switch mechanism of the iron when the iron is placed on the base for the heating action, and breaking the circuit connections 65 above-described when the iron is removed from the base, as will be readily understood.

Reference is made to Figure 2 and Figures 12 to 14, inclusive, for a clear understanding of the operation of the switch mechanism in 70 its adjustments to different positions from a neutral position to cut off current from the resistance units or to supply current for the purpose of heating such resistance units as required to heat the iron to a determined 75 temperature within any given time. As stated, the parts 9 and 22 represent one pole (for example, the negative pole) of the circuit, coupled to the negative wire of the conductor 50 through the contact 52, while the parts 23 and 53 represent the other or positive pole of the circuit when brought together, part 53 being connected to the positive wire of conductor 50, and such poles being capable 80 of connection for current flow when the iron 85 is seated on the stand, but being normally electrically disconnected. Figure 2 shows the parts of the switch mechanism in the position they occupy when the hand wheel 40 is in zero 90 position, in which position both switch plates 95 28 and 29 are out of connection with the contacts 25, 26, 26', 26^b and 27, from which it will 100 be understood that no flow of current is permitted through the resistance units. When the hand wheel 40 is turned to the indicating 105 position marked 1, parts of the switch mechanism will be adjusted to the position shown in Figure 12, in which contact brush 26' of switch plate 28 will engage contact piece 26, while contact brush 27' of switch plate 29 will 110 engage contact member 27. Current will thus be allowed to flow from pole 53 through contact 24 to pole plate 23, contacts 27—27', binding post 18, through coil winding 21 to junction point 16, thence through coil winding 20 115 to binding post 17, contacts 26—27', switch plates 28, lever 29, plate 22 and bolt 9 to the opposite pole 52, whereby current is caused to flow through both resistance units 20 and 21 for a maximum heating effect. When the hand wheel 40 is turned to the position 120 marked 2, the switch mechanism will be adjusted to the position shown in Figure 13, in which the switch plates will be swung to the opposite position from that shown in Figure 130

12 and in which brush 25' engages with brush 25 and brush 26' engages with contact 26^a, thus bringing all of resistance unit 21 and a number of turns of resistance unit 20 into a closed circuit. As a result current will flow from pole 52 to and through contact 24 to switch plate 29, to binding post 17 through contacts 25—25', through coil unit 20 to junction point 16, through a portion of coil unit 21 to and through contacts 26^a—26' to switch plate 28, and thence through lever 36, plate 22 and bolt 9 to the opposite pole 52. When the hand wheel 40 is moved to the position marked X, the switch mechanism is adjusted 15 to the position shown in Figure 14, in which position switch member 29 is shifted to bring its brush 27' into engagement with contact 27, and switch member 28 is shifted to bring its brush 26' into engagement with contact 26^b, thus bringing all of resistance unit 20 and a part of resistance unit 21 into a closed circuit. Current will then flow from pole 53 through contact 24, plate 23, switch member 25 and contacts 27 and 27' to coil winding 21, through 20 said winding to junction point 16, through a portion of coil 20 to contact 26^b, and from said contact through brush 26', to switch member 28, lever 36, plate 22 and bolt 9 to the other pole 52. The adjustment of the switches to 25 the positions shown in Figures 13 and 14 provides for a reversal of the current flow through the resistance units so that by proper arrangement of contacts 26^a—26^b, each of which may be placed at any desired turn in 30 the unit with which it is connected, two possible variations or reductions from a full heating action, such as secured by the switching arrangement illustrated in Figure 12, may be obtained, and which may vary from each other within any determined caloric ranges 35 found necessary or deemed desirable. By properly positioning one or the other of the contacts 26^a—26^b in its winding at or near the junction point 16, in the event of such winding being burnt out between the contact 40 therein and the associated binding post 17 or 18, the current may be directed to utilize the other winding for a heating action, as will be readily understood. Movement of the hand 45 wheel from any of such positions back to the zero position will result in the shifting of the switch mechanism to the position shown in Figure 2, in which, while the contact members 16 and 52 and 24 and 53 may still be in engagement with each other, no current can flow 50 through either resistance unit.

It will be seen from the foregoing description that a construction of iron is provided which carries its electrical heating element, and means for controlling the supply of current thereto, but in which the current supplying connections, including the conductor core, are wholly disassociated from the iron, so that the iron may be used like any 60 ordinary iron, without appendages or inter-

fering connections, or others liable to cause danger or trouble in service through movements of the iron, breakage of wires or accidents of other kinds. Also that the invention provides a stand or base on which the iron may be rested when not in use, and which base carries the current supplying connections for furnishing a current to the resistance coils for the purpose of heating the iron, and that through the switch mechanism on the iron body, the resistance units thereon may be coupled to or uncoupled from said current supplying connections, so that the base may be used as a conductor connection for the iron when desired or as an ordinary rest for 65 the iron when desired. As the base may be mounted in fixed position at any point, and the current supplying connections thereon and coupled thereto are not subject to breakage or derangement from movements, it is 70 obvious that greater safety, comfort and convenience are afforded in the use of a base of this character with permanently mounted current supplying connections entirely separate from the iron itself. It will be observed 75 that the simple act of placing the iron in position upon the stand will dispose it in position so that, through its switch mechanism, current will be supplied for the purpose of heating the iron through the heating units as 80 desired, and that, when the iron is removed from the base, the current supply is automatically cut off, irrespective of the position of the switch mechanism, thus giving additional degree of safety.

In practice, the body of the iron, including its acting bottom surface, 4, may be made of metal or any suitable conducting material, but I preferably make the iron body of an electric non-conductor, such as porcelain, 85 as this material, besides being a non-conductor of electricity, and hence affording greater safety against short-circuits or shocks, possesses the capacity of absorbing and storing heat to a very high degree and of retaining the heat for a longer period than metal, so that heat losses due to radiation when the iron is heated but not in actual use, will be reduced to a large extent, avoiding waste of 90 time and current incident to such losses and the necessity of heating the iron at frequent periods to maintain a working heat.

Having thus fully described my invention, I claim:

1. In an electrically heated sad iron, an iron body, a resistance unit in said iron, contacts carried by the body, one thereof being exposed through the iron face, a supporting stand for the iron, pole pieces carried by said stand for engagement with said contacts when the iron is placed thereon, and means for connecting a current supply conductor with said pole pieces.

2. An electrically heated sad iron and stand therefor, comprising an iron body, a

resistance unit therein, a contact exposed through the face of the body and electrically connected with a terminal of said unit, a contact carried by and overlying the heel of the body and electrically connected with a terminal of said unit, a supporting stud, a pole piece exposed upon the surface of the stand for engagement with the first-mentioned contact, a pole piece carried by and exposed at the rear of said stand for engagement with the heel contact, and means for supplying current to said pole pieces.

3. In an electrical sad iron and stand therefor, a hollow iron body, a resistance unit in said body, a contact exposed on the face of the iron adjacent the nose thereof and having electrical connection with one end of said unit, a contact member overlying the heel of the body and electrically connected with the other end of the unit, a supporting stand for the iron, a pair of electrical conductors extending longitudinally therethrough, a pole piece connected with one conductor and exposed through the surface of the stand for contact with the nose contact of the iron when placed on the stand, and an upstanding pole piece projecting from one end of the stand for engagement with the heel contact of the iron.

30 In testimony whereof I affix my signature.
MANUEL HUMBERTO PÉREZ.
